US00D796029S

(12) **United States Design Patent** (10) **Patent No.:** **US D796,029 S**
(45) **Date of Patent:** **** Aug. 29, 2017**

(54) **COLOSTOMY APPLIANCE**

(71) Applicant: **B. Braun Medical SAS**,
Boulogne-Billancourt (FR)

(72) Inventors: **David Hanuka**, Ramat-Yishai (IL);
Meir Or, Doar-Na Misgav (IL); **Refael Sommer**, Nesher (IL); **Tamir Shavit**, Doar-Na Galil Maaravi (IL)

(73) Assignee: **B. Braun Medical SAS**,
Boulogne-Billancourt (FR)

(**) Term: **14 Years**

(21) Appl. No.: **29/493,018**

(22) Filed: **Jun. 5, 2014**

(30) **Foreign Application Priority Data**

Dec. 9, 2013 (IL) 54859

(51) **LOC (10) Cl.** 24-02

(52) **U.S. Cl.**

USPC **D24/118**

(58) **Field of Classification Search**

USPC D24/108, 112-114, 118, 127, 128, 129,

Clark & Elbing LLP

(57) **CLAIM**

The ornamental design for a colostomy appliance, as shown and described.

DESCRIPTION

FIG. 1 is a front, perspective view of a colostomy appliance shown with the cover removed for ease of disclosure; FIG. 2 is a rear view thereof showing the cover attached; FIG. 3 is a front, perspective view thereof; FIG. 4 is a right side view thereof; FIG. 5 is a top view thereof; FIG. 6 is a front view thereof; FIG. 7 is a bottom view thereof; FIG. 8 is a left side view thereof; FIG. 9 is a side view thereof showing the cover removed, with the bag portion in a deployed configuration; FIG. 10 is a rear view thereof; FIG. 11 is a front perspective view thereof; and, FIG. 12 is a rear perspective view thereof.

The broken lines shown in FIGS. 1-12 illustrate portions of the colostomy appliance that form no part of the claimed design.

1 Claim, 6 Drawing Sheets
